CARBURETOR CONTROL FOR MOTOR CARS

Aubrey W. Barker and Barrie R. Barker, Gladwyne, Pa.

Application January 30, 1930, Serial No. 424,496

7 Claims. (Cl. 261—69)

Objects of the present invention are to eliminate fuel waste through the idling jet or jets when a motor car is coasting down grade with the throttle closed and the clutch engaged; to effect economy in the use of gasoline or like fluid fuel; to automatically cut off the supply from the carburetor to the engine when the vehicle is coasting against a running engine and to permit the fuel to flow to the idling jet only when the motor requires it.

To these and other ends hereinafter set forth or appearing, the invention, generally stated, comprises means for eliminating fuel waste through the idling jet of a carburetor associated with a throttle valve and with an engine intake manifold and clutch, which include a normally open valve arranged between the bowl of the carburetor and the Venturi tube, an electro-magnetic device, for example, and its circuit connections adapted to effect closing of the valve, and a circuit controller for the circuit connections having an actuating diaphragm exposed to and operated by the high degree of vacuum in the manifold when the throttle is closed and the clutch engaged, as in coasting. A mechanically connected device responsive to the vacuum in the intake manifold may also be used.

The invention also comprises the improvements to be presently described and finally claimed.

In the following description reference will be made to the accompanying drawings forming part hereof and in which

Figure 1 is a diagrammatic and schematic sectional view generally in elevation illustrating features of the invention.

Figure 2 is a similar view illustrating a modification of the invention, and

Figure 3 is a diagrammatic view showing a modification which is mechanically operated.

Referring to the drawing, and more particularly to Figure 1, 1 indicates an idling jet or jet tube. 2 is the throttle valve. The clutch is not illustrated because it is too well understood to require illustration or description. These are the ordinary provisions of a power plant of an automobile or like vehicle or conveyance. 4 is a normally open valve arranged between the bowl 5 of the carburetor and the idling jet 1 and the main jet 18. As shown the valve consists of a ball 6 adapted by gravity to normally occupy the cavity provided for it in the passage 7 that extends from the carburetor bowl and communicates with the idling jet passage 1. 8 is an electro-magnet which, when energized, moves the ball into position for closing the passage 7 and thus sealing

off the idling jet 1 and the main jet 18. The circuit connections for the electro-magnet are indicated as including the storage battery 9 and the conductors 10 and 11. 12 is a circuit controller and it includes an actuating diaphragm 13 exposed to the atmosphere on one face and exposed on the other face to pressure conditions in the internal combustion engine by way of the tube or connection 14.

The mode of operation may be described as follows:

With the engine running and the clutch in engagement and the car coasting, the throttle 2 is closed. Under these conditions there is a high degree of vacuum in the manifold 3, so that atmospheric pressure on the diaphragm causes it, in the present instance by shifting the upper contact of the controller 12 into engagement with the lower contact, to close the circuit, energize the electro-magnet 8, and close the valve 4, thus preventing fuel from reaching the idling jet 1 and consequently effecting a saving of fuel. This saving of fuel is quite substantial and in at least one instance has amounted to 10%.

The construction and mode of operation of the modification illustrated in Fig. 2 are substantially as above described except that the ball valve 6^a is spring pressed, for example, by the spring 15 into open position and is closed by the magnet 8^a when energized. Furthermore the parts referred to are arranged in a fitting 17 adapted to be mounted through the wall of the Venturi tube so that a device embodying features of the invention can be applied to existing structures. In this modification only the idling jet 1 is closed, it being preferable to leave the main jet 18 full of fuel to provide for immediate speeding up of the engine on opening the throttle valve 2.

The modification shown in Figure 3 operates in the same manner as the preceding modifications save that the valve is mechanically operated from the diaphragm 13 instead of being electrically operated. Also in this modification the valve 6^b is placed directly opposite the idling jet 1 and may be arranged so as to shut off only the idling jet 1 from the fuel supply passage 7 or to disconnect both the idling jet 1 and the main jet 18 from the passage 7. It is preferable to only shut off the idling jet 1 as then fuel is supplied to the main jet 18 when the throttle valve 2 is opened.

In this modification the diaphragm 13 is connected to the intake manifold by a pipe 14 as in the preceding modifications. The diaphragm

13 is also connected by the lever 19 to the valve 6^b and actuates the valve 6^b thereby.

It will be obvious to those skilled in the art to which the invention relates that modifications 5 may be made in details of construction and arrangement and matters of mere form without departing from the spirit of the invention which is not limited to such matters or otherwise than the prior art and the appended claims may require.

We claim:

1. Means for eliminating fuel waste through the idling jet of a carburetor associated with a throttle valve and with an engine intake conduit 15 comprising, in combination, a normally open valve arranged between the bowl of the carburetor and the idling jet, an electromagnetic device and its circuit connections adapted to effect closing of the valve, and a circuit controller for said 20 circuit connections having an actuating diaphragm exposed and responsive to a high degree of vacuum in the conduit when the throttle is closed.

2. Means for eliminating fuel waste through 25 the idling jet of a carburetor associated with a throttle valve and with an engine intake conduit comprising, in combination, a ball valve arranged between the bowl of the carburetor and the idling jet and adapted to open by gravity, an electro- 30 magnet and its circuit connections adapted to close the ball valve when energized, a circuit maker and breaker interposed in said circuit connections, a diaphragm for normally opening the circuit breaker, and connections between one face of the 35 diaphragm and the interior of the conduit.

3. In a device for preventing unnecessary consumption of fuel in an internal combustion engine, said device including an internal combustion engine which forms a high vacuum when the 40 engine is turning over under light load or under no load, the combination of a carburetor for supplying fuel and air to said engine, a throttle valve in said carburetor, an idling jet in said carburetor between said engine and said throttle valve 45 through which fuel but no air is supplied to said engine, a valve controlling the supply of fuel to said idling jet, means responsive to the degree of vacuum in said engine for closing said valve when the vacuum has risen to a predetermined degree without admitting air to said engine, and means for opening said valve when said first mentioned means is not operating thereby supplying fuel but no air through said idling jet to said engine.

4. In a device for preventing unnecessary consumption of fuel in an internal combustion engine, said device including an internal combustion engine which forms a high vacuum when the engine is turning over under light load or 50 under no load, the combination of, a carburetor for supplying fuel and air to said engine, an idling jet in said carburetor through which fuel but no air is supplied to said engine, a main jet in said carburetor for supplying fuel to said engine, a valve controlling the supply of fuel to 55 said idling jet and independent of the supply of fuel to said main jet, means responsive to the

degree of vacuum in said engine for closing said valve when the vacuum has risen to a predetermined degree without admitting air to said engine, and means for opening said valve when said first mentioned means is not operating thereby 80 supplying fuel but no air through said idling jet to said engine.

5. Means for eliminating fuel waste through the idling jet of a carburetor associated with a throttle valve and with an engine intake conduit comprising, in combination, a valve arranged between the bowl of the carburetor and the idling jet and stressed to open position, an electro-magnet and its circuit connections adapted to close the valve when energized, a normally open circuit maker and breaker interposed in said circuit connections, and means responsive to the degree of vacuum in said intake conduit for closing said circuit breaker when the vacuum has risen to a predetermined degree. 85

6. In a device for preventing unnecessary consumption of fuel in an internal combustion engine, said device including an internal combustion engine which forms a high vacuum when turning over under light load or under no load 100 and a higher vacuum when driven by external means with the throttle closed, the combination of a carburetor for supplying a combustible mixture of air and fuel to said engine, a throttle valve for controlling the normal supply of combustible mixture from said carburetor to said engine, means for introducing air to said carburetor, means for introducing fuel to said carburetor, means for supplying an auxiliary supply of combustible mixture to said engine when said engine 105 is under light load or no load, a valve controlling the entire supply of fuel to said last mentioned means, and means for actuating said valve arranged to close said valve while a predetermined degree of vacuum exists in said engine without admitting air to said engine. 110

7. In a device for preventing unnecessary consumption of fuel in an internal combustion engine, said device including an internal combustion engine which forms a high vacuum in turning over under light load or under no load, the combination of, a carburetor for supplying a combustible mixture of air and fuel to said engine, a throttle valve for controlling the normal supply of combustible mixture from said carburetor 115 to said engine, means for introducing air to said carburetor, means for introducing fuel to said carburetor, means for supplying an auxiliary supply of combustible mixture to said engine when said engine is under light load or no load, a valve controlling the entire supply of fuel to said last mentioned means, an electro-magnet for actuating said valve, circuit connections for said electro-magnet, a circuit maker and breaker in said circuit connections, and means responsive to the 120 vacuum in said engine for closing said circuit maker and breaker while a predetermined degree of vacuum exists in said engine without admitting air to said engine. 125

8. In a device for preventing unnecessary consumption of fuel in an internal combustion engine, said device including an internal combustion engine which forms a high vacuum when the engine is turning over under light load or under no load, the combination of, a carburetor for supplying a combustible mixture of air and fuel to said engine, a throttle valve for controlling the normal supply of combustible mixture from said carburetor 130 to said engine, means for introducing air to said carburetor, means for introducing fuel to said carburetor, means for supplying an auxiliary supply of combustible mixture to said engine when said engine is under light load or no load, a valve controlling the entire supply of fuel to said last mentioned means, an electro-magnet for actuating said valve, circuit connections for said electro-magnet, a circuit maker and breaker in said circuit connections, and means responsive to the 135 vacuum in said engine for closing said circuit maker and breaker while a predetermined degree of vacuum exists in said engine without admitting air to said engine. 140
